UNITED STATES PATENT OFFICE

TEMPERATURE CONTROL FOR LIQUIDS

Frank J. Marchak, Austin, Tex.

Application January 6, 1947, Serial No. 720,356

3 Claims. (Cl. 277—12)

1

This invention relates to new and useful improvements in temperature controls and more particularly to a device adapted to regulate the temperature of water leaving a spigot.

The primary feature of this invention is to provide a device of the character referred to adapted for attachment to hot and cold water supply pipes, thereby regulating the temperature of the water leaving a single outlet provided in the device.

Another important feature of the invention is to provide a device of the character referred to including a regulating pointer, said pointer co-operating with a slidable valve for regulating the volume of hot and cold water passing through the device.

A further feature of the invention is to provide a device for controlling the temperature of water that is easily and quickly attached to cold and hot water supply pipes.

A still further important feature of this invention is to provide a device of this character that is strong and durable in construction, neat and attractive in appearance, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which—

Figure 1 is a front elevational view of the temperature controlling device for liquids.

Figure 2 is a rear elevational view thereof.

Figure 3 is a transverse sectional view taken on a line 3—3 of Figure 1.

Figure 4 is a front elevational view with the cover plate removed.

Figure 5 is a perspective view of the slidable valve.

Figure 6 is a perspective view of connecting arm between the valve and pointer arm.

Referring now to the drawings in detail wherein, for the purpose of illustration, I have disclosed a preferred embodiment of the invention, the numeral 5 represents generally a housing formed of a forward cover plate 6 and rear plate 7, said plates being held together by a plurality of screws 8 which extend through the forward plate and into the rear plate.

A pair of inlet ports 9 and 10 are provided at the rear of plate 7, said ports being integrally cast with said rear plate 7.

When the pointer is in this position, as shown clearly in Figure 1, the arm 18 is in a vertical position and valve plate 17 is centered, thereby partially closing chambers 14 for the inlet ports 9 and 10 a substantially equal amount.

For a desired change in temperature of the water mixed in chamber 16, knob 26 is turned slightly until the pointed end 28 of pointer arm

27 opposes the desired graduation in the tempera-

ture graduated scale 29 formed on the outer face of the plate 6.

When the pointer is in this position, as shown clearly in Figure 1, the arm 18 is in a vertical position and valve plate 17 is centered, thereby partially closing chambers 14 for the inlet ports 9 and 10 a substantially equal amount.

For a desired change in temperature of the water mixed in chamber 16, knob 26 is turned slightly until the pointed end 28 of pointer arm

27 opposes the desired graduation in the tempera-

ture graduated scale 29 formed on the outer face of the plate 6.

When the pointer is in this position, as shown clearly in Figure 1, the arm 18 is in a vertical position and valve plate 17 is centered, thereby partially closing chambers 14 for the inlet ports 9 and 10 a substantially equal amount.

For a desired change in temperature of the water mixed in chamber 16, knob 26 is turned slightly until the pointed end 28 of pointer arm

27 opposes the desired graduation in the tempera-

ture graduated scale 29 formed on the outer face of the plate 6.

When the pointer is in this position, as shown clearly in Figure 1, the arm 18 is in a vertical position and valve plate 17 is centered, thereby partially closing chambers 14 for the inlet ports 9 and 10 a substantially equal amount.

For a desired change in temperature of the water mixed in chamber 16, knob 26 is turned slightly until the pointed end 28 of pointer arm

27 opposes the desired graduation in the tempera-

ture graduated scale 29 formed on the outer face of the plate 6.

When the pointer is in this position, as shown clearly in Figure 1, the arm 18 is in a vertical position and valve plate 17 is centered, thereby partially closing chambers 14 for the inlet ports 9 and 10 a substantially equal amount.

For a desired change in temperature of the water mixed in chamber 16, knob 26 is turned slightly until the pointed end 28 of pointer arm

27 opposes the desired graduation in the tempera-

ture graduated scale 29, and the lower end of arm 19 is swung toward one side, thereby sliding valve 13 to close one of the chambers 14 more than the other and thus adjust the proportion of hot and cold water entering chamber 16.

By moving the straight ends of the valve 13 across the square chambers 14, equal movements of the knob 26 provides equal opening and closing of the chambers 14 whether the end of the valve is positioned at the center of the chamber 10 or adjacent the side edges thereof and accordingly an equal change in temperature is effected.

A discharge port 30 is provided at the lower end of plate 6 and extending outwardly therefrom, said discharge port being adapted to furnish an outlet means for the desired temperature of mixed water in the mixing chamber 16.

A second outlet port 31 is provided in rear plate 7 for receiving an outlet pipe leading to a shower, or other means. This outlet port 31, when not in use, is conventionally plugged and, when in use, the port 30 is plugged, thereby causing more pressure to be maintained in the housing 5.

In view of the foregoing description taken in conjunction with the accompanying drawings, it is believed that a clear understanding of the construction, operation and advantages of the device will be quite apparent to those skilled in this art. A more detailed description is accordingly deemed unnecessary.

It is to be understood, however, that even though I have herein shown and described a preferred embodiment of my invention that the same is susceptible to certain changes fully comprehended by the spirit of the invention as herein described and within the scope of the appended claims.

What I claim is:

1. In a device of the class described, a housing including rear and forward cover plates, said rear cover plate having a pair of inlet ports, one of said inlet ports for hot liquid, the other port for cold liquid, a shaft journaled for rotation in the upper portion of the housing, the outer end of said shaft extending outwardly from the forward cover plate of the housing, a finger gripping knob mounted on the outer end of the shaft adapted for revolving the shaft, a pointer arm connected at one end to the shaft, said forward cover plate having graduations on its outer face over which the other end of the pointer arm is movable, a cylindrical valve slidably carried by the rear cover plate and arranged to open and close the ports, a pin projecting from the valve medially the length thereof, an arm secured to the shaft and having a longitudinal slot receiving the pin to slidably actuate the valve upon a rotation of the shaft, said arm being disposed between said forward

and rear cover plates, and a plurality of discharge ports in the lower end of the housing, said ports being formed in the respective rear and cover plates.

5 2. A mixing valve comprising a valve housing composed of two detachably connected sections, one of said sections having a pair of inlet ports, a slidable cylindrical valve in the housing having an undisturbed outer surface, said valve being supported on one of said sections, a chamber between each port and the valve, said valve having straight ends movable across the respective chambers and said chambers having straight right angle walls to effect equal opening or closing areas in the chambers by like movements of the valve, a shaft journaled for rotation on both of said sections, and an operating arm interposed between said sections and projecting laterally from said shaft, said arm being slidably and pivotally secured to said valve.

15 3. A mixing valve comprising a valve housing having a pair of inlet ports, a slidable cylindrical valve in the housing having an undisturbed outer surface, a chamber between each port and the valve, said valve having straight ends movable across the respective chambers and said chambers having straight right angle walls forming substantially square openings, and operating means for the valve and including a shaft journaled on both sections of the housing and an arm slidably and pivotally connected to the valve, said valve opening and closing equal areas of the chambers upon like movements of the operating means, said housing being composed of first and second detachably connected sections, the first section slidably supporting the valve, said arm being interposed between said sections, said arm being disengaged from said valve and said shaft being disengaged from said first section upon removal of said second section from said first section.
